UNITED STATES PATENT OFFICE.

JOHN HYSLOP, JR., OF ABINGTON, MASSACHUSETTS.

NAILING-MACHINE.

SPECIFICATION forming part of Letters Patent No. 429,528, dated June 3, 1890.

Application filed July 10, 1889. Serial No. 317,034. (No model.)

To all whom it may concern:

Be it known that I, JOHN HYSLOP, Jr., a citizen of the United States, residing at Abington, in the county of Plymouth and State of Massachusetts, have invented certain Improvements in Nailing-Machines, of which the following is a full, clear, and exact description, reference being had to the accompanying drawings, making part of this specification, in which—

Figure 1 is a side elevation of a nailing-machine embodying my invention, one of the two nail-reservoirs being omitted. Fig. 2 is a front elevation of the same with the front plate removed. Fig. 3 is a plan of the same. Fig. 4 is an elevation of a portion of the front of the machine. Fig. 5 is a horizontal section of the nail-carrying cylinder on the line $x x$ of Fig. 2. Fig. 6 is a longitudinal vertical section of the machine. Fig. 7 is a vertical section on the line $y y$ of Fig. 3. Fig. 8 is a plan of the nail-carrying cylinder and the lower portions of the two chutes which co-operate therewith. Fig. 9 is a sectional elevation of the nail-carrying cylinder and a portion of its operating mechanism on the line $z z$ of Fig. 8. Fig. 10 is a sectional detail of the lower portion of one of the nail-feeding chutes and the nail-carrying cylinder.

My invention has for its object to produce a nailing-machine in which nails of two kinds, sizes, or shapes, or composed of two different substances, can be alternately driven into the stock, whereby novel and ornamental effects hitherto unattainable in machines of this character can be produced without any adjustment or changing of the parts of the machine during the operation.

To this end my invention consists in a nailing-machine provided with two separate and independent nail-reservoirs adapted to contain two different kinds or sizes of nails, combined with two nail chutes or tracks connected with said reservoirs and adapted to automatically feed therefrom two different kinds or sizes of nails, said nails being taken alternately, first a single nail of one kind from one reservoir and chute and then a single nail of another kind from the other reservoir and chute, and transferred to a position beneath the nail-driver, by which they are sub-

sequently driven into the stock, as hereinafter set forth.

My invention also consists in certain novel combinations of mechanical devices and details of construction, as hereinafter set forth and specifically claimed.

In the said drawings, A represents the frame-work or head of the machine, which is of suitable shape to support the working parts and is mounted, as usual, on a post or standard B, the upper portion only of which is shown.

C is the main or driving shaft, which revolves in suitable bearings and carries the driving-pulley D and loose pulley E, the driving-pulley having secured to it a balance-wheel G, and both being adapted to turn loosely upon the shaft C, except when connected therewith by a clutch mechanism, which is operated when the machine is to be started or stopped by means of a rod b and treadle (not shown) in a well-known manner. The shaft C has secured to its front end a lifting-cam c of such shape as to lift the driver-bar H and at the proper time release the same to permit it to be thrown down quickly by its spring I, the nail-driver d, attached to the said driver-bar, acting at such time to drive the nail, as hereinafter described.

K is the work-supporting horn or rest, which is removably secured to the upper end of a vertical rod e, sliding in guides in the standard B and surrounded by a spiral spring f, which presses the work up against the feed-roll, to be hereinafter described, said rod being adapted to be depressed in a well-known manner against the resistance of the spring f by means of a treadle. (Not shown.)

LL represent a pair of nail-receiving drums or reservoirs, which are arranged on opposite sides of the machine, and with these reservoirs are connected two nail chutes or tracks N N, which are inclined downward and toward each other, as seen in Figs. 2, 3, and 8. Each of these reservoirs is open on one side to receive the nails and is supported and rotated upon a stud projecting from an arm bolted to the frame A. The two reservoirs may be supplied with nails of two different kinds, sizes, or shapes, or composed of two different substances, so that a different kind

of nail will be fed from each chute, or the two reservoirs may be both supplied with the same kind of nails when the machine is to be used for ordinary work.

5 Against the open side of each reservoir L is placed a stationary concavo-convex apron M, which extends up to about the center of the said drum, leaving the upper half open on that side to allow of the introduction of 10 the nails.

Within each drum, around its inner periphery, are arranged a series of buckets h, Fig. 2, which pick up the nails in small quantities as the drum revolves and drop them 15 onto the upper end of the inclined chute or track N, which passes through the apron M into a position to receive the nails. These drums are each provided on one side with a ratchet-wheel i, Fig. 7, with which engages a 20 pawl k on a lever l, both levers l l being actuated by the same cam m on the main shaft against the resistance of springs o o, whereby the nail drums or reservoirs are rotated intermittently as desired.

25 The inclined chutes or tracks N N are each composed of two parallel bars set at such distance apart as to leave a space or raceway p between them for the reception of the shanks of the nails, the heads of which rest upon 30 and are supported by the upper edges of the raceway, as seen in Fig. 10, by which they are guided as they slide down to the lower end thereof, and these chutes N N are each provided with suitable devices for insuring 35 the proper delivery of the nails thereto and their passage down the same in a correct position, and also for preventing the nails from becoming clogged or obstructed in their passage through the same.

40 The nail-feeding chutes and devices connected therewith, together with the nail-receiving drums and their operative mechanism, are substantially the same in construction and mode of operation as similar parts 45 shown and particularly described in another application for Letters Patent filed by me in the United States Patent Office July 10, 1889, Serial No. 317,033, and, as they form no part of this invention, will not be herein further 50 described. Nailchutes or tracks of any other suitable construction may, however, be employed, if preferred.

The nails are taken alternately from the 55 lower ends of the two chutes N N and transferred to a position beneath the nail-driver by a suitable transferring device or mechanism. One device or mechanism which I have found to answer well for this purpose will now be described; but other devices or mechanism for alternately transferring the nails from the two chutes to a position beneath the nail-driver may be employed without departing from the spirit of my invention.

60 P is a reciprocating or oscillating cylinder, 65 which is supported upon a vertical stud q, screwed at its upper end into the frame A, as seen in Fig. 6. This cylinder is provided at

its periphery with two vertical grooves, in each of which are pivoted a pair of levers r, of the form seen in Figs. 9 and 10, which are 70 pressed forward, so that their lower ends touch each other, by flat springs s, placed behind them, as seen in Fig. 9, these levers being properly centered by the contact of their upper ends with the sides or walls of 75 the grooves in which they are pivoted. The two opposite surfaces of each pair of levers r form a nail-receiving channel t, within which the nail drops, and by which it is caught and held, so that its point will not project below 80 the bottom of the cylinder. These levers also cause the nails to be properly centered over the work when carried by the oscillations of the cylinder P beneath the nail-driver, which latter, as it descends into the nail-channel t beneath it, forces the nail therein down between the lower ends of the levers r, which are thus separated against the resistance of 85 their springs s to allow of the passage of the nail into the stock on the work-supporting 90 horn or rest beneath, the levers being closed together or returned to their normal positions by the said springs on the ascent of the nail-driver. The nail-receiving channels t are of 95 rectangular form in horizontal section, with the longer dimension pointing radially toward the center of the cylinder, which enables them to receive and hold nails having rectangular heads, which are thus prevented from turning in the said channels, the levers 100 r being provided at their lower ends with elliptical cavities, into which the flat point of the nail settles, causing the point of the nail to lie directly under the head, which insures 105 the nail being driven into the material perfectly straight.

Around the lower half of the cylinder P is immovably secured a tightly-fitting collar or sleeve b', which serves to cover the nail-channels t and confine the nails therein. 110 This collar is provided on its exterior surface with two notches or cavities c', Figs. 2 and 5, one for each nail-channel t, these notches being engaged by a spring-catch d', which thus locks and holds the cylinder P at the termination of each movement immovably in its 115 proper position, with one of its nail-channels directly beneath the nail-driver, so that it cannot turn in either direction while the nail is being driven, the cylinder when in this position having its other nail-channel in line with the chute from which it is supplied with 120 nails, whereby a nail is taken from each one of the chutes at the same time that the nail previously taken from the other chute is being 125 driven into the stock by the nail-driver. The spring-catch d' is disengaged from the notch c' at the proper time to permit the cylinder to be oscillated in the opposite direction by an arm e', connected with a lever 28, which 130 is operated by a cam or projection f' on the main shaft, against which it is constantly held by the pressure of the spring-catch d' on the arm e'.

The cylinder P is oscillated or reciprocated at the proper times to bring its two nail-channels *t* alternately opposite to their respective chutes N N, whereby a nail is taken 5 alternately from each chute and transferred to a position beneath the nail-driver, which then descends and drives the nail into the stock. On the ascent of the nail-driver the cylinder P is oscillated in the opposite direction, 10 which brings the empty nail-channel last beneath the nail-driver opposite to the end of its chute N to receive another nail, which movement brings the other nail-channel, into which a nail has just been deposited from the 15 chute which co-operates therewith, beneath the nail-driver to be driven in the same manner as the previous one, and in this manner nails of two different kinds, sizes, or shapes, or composed of two different substances, can 20 be alternately driven into the stock to produce novel and ornamental effects, each of the nail-reservoirs being supplied with the particular description of nails desired.

To the top of the cylinder P is secured a 25 cap *g'*, which is provided at its periphery with two radial slots *h'*, corresponding to the nail-channels *t* and placed immediately thereto. The outer portions of these slots *h'* are of such size as to admit the shank of a nail, 30 but not the head, which rests on the edges of this portion of the slot, while the inner portion of the slot is enlarged and is of such size and shape as to allow the nail to drop through it into the nail-channel *t* beneath, 35 and also permit of the passage of the nail-driver, which passes through the said enlarged portion of the slot. As each nail drops to the lower end of its chute N, it is caught and held by an adjustable stop *i'*, which is secured 40 to the end of the chute and extends beyond the same over the nail-cylinder, as seen in Fig. 10, just far enough to allow the lowermost nail in the chute to slide into the narrow portion of the slot *h'* opposite thereto, 45 but no farther, whereby the entrance of more than one nail at a time into the slot is prevented and the clogging of the nail-channels thus avoided, and as the cylinder is oscillated the projecting head of the nail is carried into 50 an eccentric or cam-groove *k'*, Figs. 8 and 9, formed in the under side of a guide-piece *l'*, adjustably secured to a guard 30, attached to the lower end of the chute. The form of the cam-groove *k'* is such that as the nail-head is 55 carried through it by the oscillation of the cylinder P it will be pushed inward toward the center of the cap *g'* until it reaches the enlarged portion of the slot *h'*, through which it will then drop into the nail-channel *t* beneath, 60 to be caught by the centering and holding levers *r*. The cap *g'* is made adjustable and removable from the cylinder P, so that it can be replaced by others having slots *h'* of different sizes or shapes for nails of different kinds. The lower end of the guard 65 30 extends downward, and is so placed that it will cover that portion of the nail-channel

which lies between the cap *g'* and the collar *b'* at the time that the nail is passing down through the cap into the said nail-channel, 70 whereby the nail is guided safely into the lower portion of the nail-channel surrounded by the collar *b'*.

The nail holding and centering levers *r* of the nail-carrying cylinder, the radial slots *h'* 75 in its cap *g'*, the collar or sleeve *b'*, which encircles the lower portion of the cylinder, as also the spring-catch *d'*, for holding said cylinder in position after each movement, the guide-pieces *l'*, with their cam-grooves *k'*, for 80 pushing the nails from the narrow into the enlarged portions of the slots *h'* in the cap *g'*, the stops *i'* at the lower ends of the chutes N N, for catching and holding the lowermost 85 nails in each of the chutes, and the guards 30, which cover the open portions of the nail-channels, are all substantially the same in construction and mode of operation as similar parts shown and described in my aforesaid application for Letters Patent of the 90 United States, filed July 10, 1889, Serial No. 317,033, and form no part of this invention.

The nail-carrying cylinder P is oscillated a distance equal to that between its two nail-channels *t* in the following manner: The upper or smaller portion of the cylinder P is encircled by a collar *n'*, secured immovably thereto, and provided with an arm *p'*, to which is pivoted a horizontal rod *q'*, which passes through an aperture at the lower end of a lever Q, fulcrumed at 31 to the frame A and provided with a longitudinal slot *r'*, Figs. 2 and 4, in which works a crank-pin *s'*, projecting from the face of a gear R, which meshes with and is rotated by a smaller gear *t'* on the 100 main shaft C, the relative sizes of the gears R *t'* being such that a single revolution of the main shaft will, through the connections described, produce a vibration of the lever Q in one direction only. On opposite sides of 110 the lower end of the lever Q the rod *q'* is encircled by two stiff spiral springs *u' v'*, the outer spring *u'* being kept in place by nuts 32 at the end of the rod *q'*, and thus as the lever Q is vibrated in either direction by the 115 rotation of the gear R its motion is communicated through one of the springs *u'* or *v'*, on which it presses, to the rod *q'* and arm *p'*, thus moving the nail-carrying cylinder, the springs *u' v'* being sufficiently stiff to perform 120 this function without yielding. If, however, the nail-carrying cylinder should become obstructed by an imperfect nail or from any cause be prevented from revolving, the lever Q, on being vibrated, will slide over the rod 125 *q'* and compress the spring located upon the side toward which it is moving without turning the cylinder P, thus avoiding the breaking or injuring of the parts which would otherwise occur. It is obvious, however, that 130 a rigid connection could be employed, if desired, between the arm *p'* and the lever Q; but I prefer a yielding connection, for the reasons above stated.

By adjusting the yielding connection between the vibrating lever Q and the arm p', which operates the nail-carrying cylinder, which is effected by means of the nuts 32, the position 5 of the cylinder P can be regulated with the utmost nicety to insure the slots h' in its cap g', and its nail-receiving channels thereunder being brought exactly into line with the nail-driver after each movement of the cylinder, 10 and the chutes or tracks N N are also made adjustable on the frame-work A by means of screws and slots, so that they can be brought exactly into a proper operative position with regard to their respective nail-channels in the 15 nail-carrying cylinder after the latter has been adjusted to bring its nail-receiving channels exactly into line with the nail-driver, as before described.

The feeding device by which the stock, 20 after each nail has been driven, is moved into the proper position for the next nail will now be described.

At the lower end of a plate T, secured to the front plate U of the machine, is formed a bearing for the support of a serrated or roughened feed-roll f², which is adapted to bear upon the stock outside the nail-driver, and to this feed-roll is immovably secured a ratchet-wheel g², the said feed-roll and ratchet-wheel being held in place within the bearing at the bottom of the plate T by a bolt h², having a nut i² and check-nut k². The ratchet-wheel g² is intermittently rotated by a pawl l² at the lower end of a bar m², the upper end 30 of which is pivoted to a block n², which slides in a vertical slot p² in the front plate U and projects inward, so as to lie in the path of a lug or projection r², Fig. 2, on the driver-bar H, the parts being so arranged that as the 35 driver-bar is raised by its cam the projection r² thereon will impinge on the block n² and raise the bar m² against the resistance of a spring, (not shown,) causing the pawl l² to turn the ratchet-wheel and feed-wheel a sufficient distance to produce the desired amount 45 of feed of the stock held between said feed-wheel and the work-supporting horn or rest by the upward pressure of the spring f, the stock being guided, as usual, by the hand of the operator and held against an adjustable 50 gage-wheel 34, which is mounted on a supporting-arm 35 and regulates the distance of the nails from the edge of the work.

To the upper end of the work-supporting horn K is secured a beveled roll s², which rotates on a pin projecting from the horn at an angle of forty-five degrees, which causes the beveled face of the roll to lie in a horizontal plane, the roll forming a support for the stock 55 outside the line in which the nails are being driven. On the inner side of the roll s² is placed a vertical work-supporting roll t², which revolves on a horizontal stud projecting from an L-shaped piece u², which is made 60 adjustable horizontally by means of a slot and screw upon the work-supporting horn K, and when the nails are to be driven 65

into the stock without clinching the roll t² is adjusted so as to leave a space or channel between it and the beveled roll s², as seen in Figs. 1 and 6, into which the points of the 70 nails enter. When, however, it is desired to clinch the nails, the roll t² is adjusted to bring it up close against the beveled or outside roll s², whereby a solid anvil is formed, against 75 which the point of the nail is driven to clinch it. These work-supporting rests or rolls are 80 fully described and claimed in my aforesaid application for Letters Patent of the United States, filed July 10, 1889, Serial No. 317,033, and, as they form no part of this invention, 85 will not be herein further described. I do not, however, limit myself to the employment of a work-supporting horn constructed as above described, as any other suitable or well-known 90 work-supporting horn or rest can be used instead, if desired, and it is obvious that the principal feature of my invention, which consists in the employment of two nail-feeding chutes, from which the nails are alternately 95 taken and transferred to a position beneath the nail-driver, may be applied to nailing machines of various constructions, if desired, thereby enabling such machines to alternately drive two different kinds of nails without changing or adjusting any of the mechanism or stopping the machine—a desideratum hitherto unattained in any nailing-machine with which I am acquainted.

I am aware that nailing-machines have 100 been provided with two or more receptacles for containing nails of different lengths or kinds, which are delivered therefrom by suitable mechanism to the point where they are driven, said mechanism being capable of adjustment at the will of the operator, so that 105 nails can be delivered from either receptacle, as may be desired. To such construction I make no broad claim, as my invention differs entirely therefrom, inasmuch as in my machine the nails are taken automatically from two separate receptacles, each provided with a chute or track, first a single nail of one kind from one chute or track and then a single nail of another kind from the other chute 110 or track, and transferred to a position beneath the nail-driver, which cannot be accomplished in any of the machines heretofore constructed in which different kinds of nails are taken from two or more receptacles, as in such machines one kind of nail is fed continuously 115 until the operator adjusts the machine to cause another kind of nail to be fed to the desired point.

What I claim as my invention, and desire 120 to secure by Letters Patent, is—

1. In a nailing-machine, a nail-driver, two separate and independent nail-reservoirs adapted to contain two different kinds or sizes of nails, two stationary nail-feeding chutes or 125 tracks connected with said reservoirs, a reciprocating or oscillating nail-carrier provided with nail receiving and holding grooves or channels and adapted to automatically take

the nails alternately, first a single nail of one kind from one reservoir and chute and then a single nail of another kind from the other reservoir and chute, and transfer the same to a position beneath the nail-driver, and mechanism for automatically reciprocating or oscillating the nail-carrier, substantially as described.

2. In a nailing-machine, the combination, 10 with a nail-driver, and a work-supporting horn or rest, and a feeding device for the stock, of two separate and independent nail-reservoirs adapted to contain two different kinds or sizes of nails, two stationary nail-feeding chutes or 15 tracks connected with said reservoirs, a reciprocating or oscillating nail-carrier provided with nail receiving and holding grooves or channels and adapted to automatically take the nails alternately, first a single nail of one 20 kind from one reservoir and chute and then a single nail of another kind from the other reservoir and chute, and transfer the same to a position beneath the nail-driver, and mechanism for automatically reciprocating or oscillating the nail-carrier, substantially as described.

3. In a nailing-machine, the combination, 25 with the work-supporting horn and a nail-driver, of two nail-feeding chutes or tracks and a reciprocating or oscillating cylinder pro-

vided at its periphery with two nail receiving and holding grooves or channels which are alternately brought by the oscillations of the cylinder automatically into line, first with one chute and then with the other, whereby the 35 nails are automatically taken alternately, first a single nail of one kind from one chute and then a single nail of another kind from the other chute, and carried to a position beneath the nail-driver, substantially as described. 40

4. In a nailing-machine, the combination, 45 with the oscillating nail-carrying cylinder P, the vibrating lever Q, and means to operate the same, of a double yielding connection between said lever Q and the cylinder P, consisting of the rod q', pivoted to the arm p' and passing through an aperture in the lower end of the lever Q, and the springs u' v', encircling said rod q' on opposite sides of the lever Q, whereby said lever is permitted to 50 move in either direction without actuating the cylinder P in case the latter should become obstructed, substantially as described.

Witness my hand this 3d day of July, A. D. 1889.

JOHN HYSLOP, JR.

In presence of—

P. E. TESCHEMACHER,
HARRY W. AIKEN.
